LATCH

Gordon E. Roedding, Grand Rapids, Mich., assignee to Grand Rapids Brass Company, Grand Rapids, Mich., a corporation of Michigan

Application February 23, 1934, Serial No. 712,531

5 Claims. (Cl. 292—221)

The present invention relates to latches; and its object is, generally, to provide an improved latch having means for securely holding the latching bolt in operative engagement with its keeper, and means for nevertheless easily retracting the bolt from such engagement; and more particularly, to provide a latch having such a bolt, a slide bearing, bolt-moving means connected to the bolt and slidable in the bearing to opposite positions wherein said means moves the bolt to operative and to retracted positions respectively, together with means for urging said bolt-moving means to one position in the bearing whereby the bolt is held in operative engagement; and means for moving the bolt-operating means to an opposite position in the bearing whereby the bolt is moved to retracted position; and also to provide resilient means for yieldingly but securely holding the bolt in operative position.

These and any other and more specific objects hereinafter appearing are attained by, and the invention finds preferable embodiment in, the illustrative structure particularly described in the body of this specification and illustrated by the accompanying drawing, in which:

Figure 1 is a central sectional view of a latch mounted in the closure of a door and of its keeper mounted in the frame of the door, the latching bolt being shown in retracted position;

Figure 2 is a like view of the same but showing said bolt in operatively engaging position with the keeper; and

Figure 3 is a sectional view of parts of the latch taken on line 3—3 of Figure 2.

The latch shown by the drawing comprises a base member or housing 1 seated in a cavity 2 in the free edge of the door's closure 3 and held therein as by screws 4. Pivotated at 5 in this housing base, the latching bolt 6 is swingably movable through the housing's opening 7 into projected operative engagement with its keeper 8 mounted on the door's frame 9. Means designated generally 10 for moving the bolt comprises the elongated member 19 pivotally connected at 13 with the bolt and the member or pin 14 slidable in the bearing, the slots 15, in the opposite walls 16 of the housing. Said elongated member 19 comprises a pair of sides 20 having longitudinally extending slots 21 through which the pin member 14 extends as seen in Figure 3.

In the position of the parts shown in Figure 2, said bolt-moving means 10 extends at right angles to the bearing 15 so that the bolt 6 is held in projecting position engaging its keeper; but when said means 10 is moved downwardly, its elongated

member 19 turns on its pivotal connection 13 on the bolt, and its other member, the pin 14 slides downwardly to the position seen in Figure 1, so that by reason of the inclined disposition of the bearing 15 the axial or longitudinal direction of the bolt-moving means 10 is now inclined relatively to its direction when the bolt is projected (Figure 2). Thus the bolt is projected and held in projected position when the pin member 14 is in the upper end of said bearing, and is retracted and held in retracted position when said pin member is in the lower end of the bearing.

A spring 17 presses between member 19 and the abutment or ledge 18 of the housing to urge said bolt-moving means 10 upwardly and its pin member 14 to the upper end of the bearing 15 and thus hold the bolt projected as shown in Figure 2; and suitable hand-operated means for moving means 10 downwardly and pin member 14 to the bottom of said bearing as shown in Figure 1, to thus retract the bolt, are provided, such means as shown being the plunger 11 slidable in bearings 12 and pushed downwardly by the lever handle 22 fulcrumed at 23 and having opposite portions 24 either of which may engage the head 25 of the plunger to press it downwardly against its spring 26.

When the closure 3 is slammed shut, the pin member 14 being in the upper end of the bearing 15, the outer edge portion 27 of the bolt 6 rides on the keeper's high point 28 thus swinging the bolt inwardly and compressing the stiff spring 29 pressing between the pin member 14 and the stop or abutment 30 of the elongated member 19 and sliding this member inwardly toward the pin 14; and when the extreme edge portion 31 of the bolt passes below the keeper's high point 28 this spring 29, being thus permitted to expand, swings the bolt outwardly in which movement the bolt's curved edge portion 32 rides on the keeper to the position seen in Figure 2 and thus securely holds the closure shut. This edge portion 32 is desirably a cam wedgingly engaging the keeper.

It will be seen that the action of the spring 29 is not affected by the upward or downward movement of the bolt-moving means 10, so that it is not affected by the movement of the spring 17 or the plunger 11 and its operating handle 22, this spring 29 functioning only to yieldingly hold the bolt outwardly into operative engagement with the keeper. It will thus be seen that although this latch securely holds the closure shut, the closure may nevertheless be opened with very little effort.

The invention being intended to be pointed

out in the claims, is not to be limited to or by details of construction of the particular embodiment thereof illustrated by the drawing or hereinbefore described.

5 I claim:

1. A latch structure comprising: a base; a latching bolt pivotally mounted thereon for projecting and retracting movements; an elongated first member pivotally connected with the bolt; 10 a second member having a limited movement relatively to said first member in the longitudinal direction thereof; a bearing in the base wherein said second member is slidable, said bearing being so disposed that the sliding movement of said second member toward one end of the bearing projects the bolt and said second member's sliding movement in the opposite direction retracts the bolt; means for yieldingly holding the bolt in projected position.
2. A latch structure comprising: a base; a latching bolt pivotally mounted thereon for projecting and retracting movements; an elongated first member pivotally connected with the bolt; 15 a second member having a limited movement relatively to said first member in the longitudinal direction thereof; a bearing in the base wherein said second member is slidable, said bearing being so disposed that the sliding movement of said second member toward one end of the bearing projects the bolt and said second member's sliding movement in the opposite direction 20 retracts the bolt; a spring pressing between said first and second members to yieldingly hold the bolt in projected position.
3. A latch structure comprising: a base; a latching bolt pivotally mounted thereon for projecting and retracting movements; an elongated first member pivotally connected with the bolt; 25 a second member having a limited movement relatively to said first member in the longitudinal direction thereof; a bearing in the base wherein said second member is slidable, said bearing being so disposed that the sliding movement of said second member toward one end of the bearing projects the bolt and said second member's sliding movement in the opposite direction 30 retracts the bolt; means for yieldingly holding the bolt in projected position; means for yieldingly urging said second member in the direction to project the bolt.
4. A latch structure comprising: a base; a latching bolt pivotally mounted thereon for projecting and retracting movements; an elongated first member pivotally connected with the bolt; 35 a second member having a limited movement relatively to said first member in the longitudinal direction thereof; a bearing in the base wherein said second member is slidable, said bearing being so disposed that the sliding movement of said second member toward one end of the bearing projects the bolt and said second member's sliding movement in the opposite direction 40 retracts the bolt; means for yieldingly holding the bolt in projected position; means for yieldingly urging said second member in the direction to project the bolt; a plunger slidable to a position engaging said elongated first member for moving said second member in the direction retracting the bolt.

said second member toward one end of the bearing projects the bolt and said second member's sliding movement in the opposite direction retracts the bolt; means for yieldingly holding the bolt in projected position; means for yieldingly urging said second member in the direction to project the bolt; means for sliding said second member in the direction to retract the bolt.

4. A latch structure comprising: a base; a latching bolt pivotally mounted thereon for projecting and retracting movements; an elongated first member pivotally connected with the bolt; 10 a second member having a limited movement relatively to said first member in the longitudinal direction thereof; a bearing in the base 15 wherein said second member is slidable, said bearing being so disposed that the sliding movement of said second member toward one end of the bearing projects the bolt and said second member's sliding movement in the opposite direction 20 retracts the bolt; a spring pressing between said first and second members to yieldingly hold the bolt in projected position.

5. A latch structure comprising: a base; a latching bolt pivotally mounted thereon for projecting and retracting movements; an elongated first member pivotally connected with the bolt; 25 a second member having a limited movement relatively to said first member in the longitudinal direction thereof; a bearing in the base wherein 30 said second member is slidable, said bearing being so disposed that the sliding movement of said second member toward one end of the bearing projects the bolt and said second member's sliding movement in the opposite direction 35 retracts the bolt; means for yieldingly holding the bolt in projected position; means for yieldingly urging said second member in the direction to project the bolt; a plunger slidable to a position engaging said elongated first member for moving said 40 second member in the direction retracting the bolt.

GORDON E. ROEDDING.
